UNITED STATES PATENT OFFICE

106,458

DESIGN FOR A PORTABLE GRINDING MACHINE

Otto St. John, Toledo, Ohio, assignor to The
American Floor Surfacing Machine Company,
Toledo, Ohio, a corporation of Ohio

Application August 2, 1937, Serial No. 70,802

Term of patent 14 years

To all whom it may concern:

Be it known that I, Otto St. John, a citizen of the United States, and resident of Toledo, in the county of Lucas and State of Ohio, have invented a new, original, and ornamental Design for a Portable Grinding Machine, of which the following is a specification, reference being had to the accompanying drawing, forming a part thereof.

Fig. 1 is a side elevation of a portable grinding machine showing my new design; Fig. 2 is a

top plan view of such machine with the motor and the parts driven thereby removed from the truck platform, and Fig. 3 is an end elevation of the parts shown in Fig. 2.

The dominant feature of my design resides in the portions shown in full lines.

I claim:

The ornamental design for a portable grinding machine, substantially as shown and described.

OTTO ST. JOHN.
